(57) **CLAIM**

The ornamental design for a seat assembly for an integrated patient for medical procedures, as shown and described.

DESCRIPTION

FIG. 1 is an elevated perspective view of a seat assembly for an integrated patient for medical procedures showing our new design;

FIG. 2 is a front view of the design of FIG. 1;

FIG. 3 is a back view of the design of FIG. 1;

FIG. 4 is a right side view of the design of FIG. 1;

FIG. 5 is a left side view of the design of FIG. 1;

FIG. 6 is a top view of the design of FIG. 1; and,

FIG. 7 is a bottom view of the design of FIG. 1.

The broken lines throughout are included for the purpose of illustrating environmental structure and form no part of the claimed design. All other broken lines are included for the purpose of illustrating portions of the article and form no part of the claimed design.
